SAFETY RAZOR HOLDER

Axel S. Carlson, Brooklyn, N. Y., assignor of one-half to Concetta L. Blue, Brooklyn, N. Y.

Application October 15, 1934, Serial No. 748,371

17 Claims. (Cl. 30—12)

My invention relates principally to the holder and, particularly, to the clamping arrangement for securing a safety razor blade in a holder.

An object and feature of my invention is the employment of a pivotally mounted clamping plate which is pivoted on the base or supporting plate of a safety razor holder and the constructional features for operating the hinged clamping plate to engage a razor blade between the clamping plate and the supporting plate.

Another feature of my invention relates to a mechanical device for exerting a pressure of the clamping plate on the blade to hold the blade snugly between the supporting plate and the clamping plate.

Another feature of my invention is a mechanism for operating both the pressure device and the clamping plate by a screw extending longitudinally of the handle of the blade holder.

Another and further detailed object of my invention is having the supporting plate rigidly connected to a handle and at one end of this supporting plate hinging the clamping plate. A screw extending through the handle and having an operating head may be rotated to raise or lower the clamping plate, this being done by an arm connected to a sliding sleeve, the arm being attached by a link mechanism to the clamping plate and swiveling this on its hinge until it may occupy a position at right angles to the supporting plate through rotating the clamping plate to this position.

A further detailed feature of my invention in connection with the pressing device is operating this directly by the screw to engage the clamping plate and pull this downwardly tightly on a blade, and also the feature of releasing the pressure device before the clamping plate may be tilted upwardly. In this connection the screw is provided with a stem extending through the supporting plate, the razor blade, and through a perforation, and engaging a groove in the clamping plate. The stem is provided with a head at the top to engage the clamping plate, this head being automatically released through the slot on the upward tilting of the clamping plate.

Other detailed features of my invention relate to the supporting of the blade between knife-like edges, the detail shape of the blade, this being provided with a center perforation for the stem of the pressure device with two transverse slots for engaging setting pins, these slots being connected to the end edge of the blade, each by a longitudinal slot, this slot accommodating at one end a stud on the supporting blade and

the link mechanism for operating the clamping plate.

Another feature of the blade is providing end tabs or projections to facilitate lifting the blade for inserting and removing from the holder. 5

My invention is illustrated in connection with the accompanying drawings, in which:

Fig. 1 is an edge elevation taken in the direction of the arrow 1 of Fig. 2.

Fig. 2 is a front elevation taken in the direction of the arrow 2 of Fig. 1.

Fig. 3 is a plan taken in the direction of the arrow 3 of Fig. 2.

Fig. 4 is a transverse section on the line 4—4 of Figs. 2, or 3, on an enlarged scale. 15

Fig. 5 is a vertical section on the line 5—5 of Fig. 1 in the direction of the arrows with the blade shown in the clamped position.

Fig. 6 is a partial section similar to Fig. 5 with the clamping plate in its open or elevated 20 position.

Fig. 7 is a section on the line 7—7 of Fig. 5, showing the blade in plan with the supporting plate thereunder.

Fig. 8 is an elevation similar to Fig. 2 with the 25 clamping plate in its opened position and the blade removed.

In constructing my invention I utilize a handle structure 11 which has a substantially circular hub section 12 with lateral fins 13. These 30 fins are to provide good finger grips. The fins are formed bulbous on the side edges 14, thus providing concave grooves 15 extending longitudinally on each side of the hub portion 12. This enables the fingers to readily grip the handle. The upper end of the handle is, preferably, circular in cross section at 16 and is provided with a longitudinal slot 17. The handle has an enlarged lower bore 18 and a reduced upper bore 19 with a shoulder 20 therebetween. The lower 40 portion, at least, of the bore 18 is internally threaded as indicated at 21.

The supporting plate 22, on which the razor blade is mounted, is formed integral with the handle and has a central perforation 23 therethrough. This clamping plate is provided with a guard 24 on each edge, the guard being in the form of a comb and having end or corner teeth 25, and intermediate teeth 26, the teeth in cross section being substantially as shown in Fig. 4. 45 There is a longitudinal slot 27 through the center portion of one end of the supporting plate and a pair of upstanding lugs 28 spaced laterally from this slot. There is a centering stud 29 extending upwardly from the end opposite the slot 27 and, 50 55

in addition, two pair of guide studs 30. For supporting the blade, the supporting blade is provided with transverse ribs 31 extending completely from one side to the other of the comb-like guards. These ribs project slightly, as indicated at 32, beyond the lateral or side edge 33 of the supporting plate. Each rib has a knife-like edge 34. At the end 35 of the supporting plate opposite that having the slot, there is a low center section 36, this being in a plane with the main upper surface 37 of the supporting plate. At the opposite end 38 of the supporting plate, that is, the end having the slot 27, there are the pair of raised lugs 28.

Through these lugs extends a pintle pin 40, to which is hinged the clamping plate designated by the assembly numeral 41. This clamping plate has a pair of depending ears 42 mounted on the pivot pin 40. The clamping plate is convexly curved transversely on its upper surface 43 and has a plane or flat lower surface 44. The lower surface is provided with transverse ribs 45, each rib having a sharpened or knife-like edge 46. The ends of the clamping plate each have a pair of downwardly extending lips 47. These lips extend outwardly laterally from the edge 48 of the clamping plate, as indicated at 49 (note Fig. 4) and form a protection against cuts by the corner of the blade. The under side 50 of the clamping plate has a recess 50 in which fits the upper end of the stud 29. There is a circular slot 51 through the clamping plate slightly opposite from the center, and extending longitudinally from this slot there is a slot 52, the slot extending slightly beyond the center of the clamping plate considered longitudinally.

The device for operating the clamping plate and for clamping this tightly employs a screw 53 having a threaded portion 54 in the threaded section 21 of the bore 18 of the handle. This screw has a projection 55 with an operating head 56, this being shown as hexagonal. A tapered section 57 of the screw leads to a stem 58 extending through the bore 18 and the contracted bore 19 and the perforation 23. There is a collar 59 on the stem and such stem has a head 60 at the top, slightly beveled at 61 on the under side of the head. A cupped sleeve 62 slides in the bore 19 and has a perforation 63 in the base 64, through which the stem above the collar 59 extends. A compression spring 65 is seated in this cup and engages the upper end 66 of the reduced bore 19. An arm 67 is attached to the cupped sleeve 62; this has what might be termed a horizontal section 68 extending through the slot 17 which extends through the section 16 of the handle. An upwardly sloping section 69 leads to a vertical section 70. This vertical section is provided with a pair of ears 71, through which extend a pintle 72. A triangularly shaped link 73 is fitted between the ears and engages the pintle. This link at the opposite end engages a pintle 74 on a pair of depending ears 75 from the clamping plate.

The blade 76 is provided with two opposite cutting edges 77, these terminating at the ends 78. Each end has a pair of notches 79 to accommodate the ears 42 on the under side of the clamping plate. There is a central longitudinal slot 80 extending inwardly from the ends, which ends have projecting portions 81, which extend slightly beyond the opposite ends of the clamping and supporting plate. At the inner end of each slot 80 there is a transverse slot 82. The slots 82 engage the studs 30 extending upwardly from

the supporting plate. The stud 29 fits in one of the slots 80, and the link 73, together with the ears 75 of the clamping plate, extend through the other slot 80. The blade has a central perforation 83 to accommodate the upper portion of the stem 58, this being of sufficient size to pass over the head 60.

The manner of using and operating my invention is as follows:

The clamping plate, the stem, and the supporting blade are in the position of Figs. 6 and 8, that is, with the clamping plate in its opened position extending upwardly from one end of the supporting plate. The blade is then placed on the supporting plate with the studs 30 extending through the slots 82, the link 73, and ears 75 being fitted in one of the slots 80, and the stud 29 in the opposite slot 80 at the end of the blade. The upper portion of the stem extends through the center perforation 83 of the blade. When the device is in this position the screw is threaded in the handle to its limit. This thrusts the head 60 of the stem upwardly considerably higher than shown in Figs. 2 and 5. The base of the sliding sleeve 62 rests on the collar 59. In order to clamp the blade, the operating head 56 of the screw 53 is rotated to thread the screw outwardly as regards the handle, which action, in lowering the collar 59, permits the spring 65 to force the cupped sleeve 62 downwardly, which action moves the clamping plate 41 from the position of Figs. 6 and 8 to the position of Figs. 1 through 5. As the clamping plate is lowered, the head 60 and the part of the stem 58 adjacent thereto passes upwardly through the perforation or slot 51 in this clamping plate, and the head engages in the groove 52.

This action brings the knife edges of the ribs on the clamping plate into engagement with the top of the blade directly opposite the knife-like edges of the ribs on the supporting plate. As the screw is tightened, the head 60 on the upper end of the stem 58 exerts a downward pull on the clamping plate and thus clamps the blade tightly between the clamping and the supporting plates. The razor blade and holder are then in position for shaving and, as above described, the flattened handle with the grooves 13 and bulbous edges 14 facilitate the holding of the handle in the hand of the person shaving. The downwardly extending lips 47 at each corner at the end of the clamping blade cover the corner edges of the blade and lessen the danger of a person cutting himself, when shaving, with these corners. The blade is released by a reverse action, that is, the screw is threaded in the handle, thus raising the stem and the head 60 and bringing the collar 59 against the base of the sleeve 62, elevating this sleeve and compressing the spring 65 at the same time. This action moves the arm 67 upwardly and rotates the clamping plate through the medium of the link 73 from the position of Figs. 2 and 5 to that of Figs. 6 and 8.

Various changes may be made in the details of construction without departing from the spirit or scope of the invention as defined by the appended claims:

I claim:

1. In a safety razor a supporting plate having a perforation, a tubular handle connected to the plate and in alignment with the perforation, a clamping plate having an elongated slot with a narrow and an enlarged portion, a stem extending through the handle, the perforation and the

slot, said stem having a head, means operating between the handle and the stem to exert a longitudinal tension on the stem to engage the head of the stem and the clamping plate at the narrow portion of the slot, said tension means being adapted to move the stem longitudinally to release the said head from the clamping plate and to elevate said head above the clamping plate, and means to swing the clamping plate in an arcuate movement in reference to the supporting plate to pass the said head through the large portion of the said slot.

2. In a safety razor as claimed in claim 1, the means to swing the clamping plate including an arm, an operating means between the stem and the said arm to elevate the arm on the upward movement of the stem and a connection between the said arm and the clamping plate to swing the clamping plate into an open position on the upward movement of the arm.

3. In a safety razor a supporting plate having a perforation, a tubular handle connected thereto and screw-threaded at its lower end, a stem extending through the handle and the perforation and having a screw at one end engaging the threads of the handle, a clamping plate having a longitudinal slot with a narrow and a wide portion, the said clamping plate when in operative clamping position being parallel to the supporting plate, a portion of the stem extending then through a narrow portion of the slot, said stem having a head to engage the upper surface of the clamping plate, the rotation of the screw in one direction exerting a tension on the stem to tightly engage the head and the clamping plate, a rotation of the screw in the opposite direction elevating the said head above the clamping plate, and means to swing the clamping plate in an arc to an open position whereby the said head passes through the wide portion of the slot in such movement.

4. In a safety razor as claimed in claim 3, the means to swing the clamping plate in an arc including the said handle having a lateral opening, an arm extending through said opening, means on the stem to raise the arm on upward movement of the head of the stem, and a connection from the opposite end of the arm to move the clamping plate from its clamping to an open position.

5. A safety razor comprising in combination, a supporting plate having a perforation, a tubular handle at right angles thereto having a threaded portion, a stem extending through the handle and the perforation and having a screw engaging the said threaded portion of the handle, a clamping plate pivotally connected to the supporting plate at one end, said clamping plate having a longitudinal slot with an enlarged and a narrow portion, the stem extending through the narrow portion when the clamping plate is parallel to the supporting plate and in clamping position, the said stem having a head to engage the clamping plate, the rotation of the screw in one direction exerting a tension on the stem to tightly clamp the clamping plate in relation to the supporting plate, the rotation of the screw in the opposite direction moving the stem and the head upwardly, and an interacting means between the stem and the clamping plate to swing the clamping plate in an arc on its pivot whereby the said head passes through the enlarged portion of the said head.

6. A safety razor as claimed in claim 5, the interacting means between the stem and the

clamping plate including the handle having a lateral slot, a sleeve in the handle, a collar on the stem to engage the sleeve on the upward movement of the stem, an arm connected to the sleeve and extending through the opening of the handle, and a pivoted link connecting the upper end of the arm and the clamping plate.

7. A safety razor having a handle, a supporting plate secured thereto at right angles to the handle, a clamping plate pivotally connected to the supporting plate at one end, said clamping plate having a slot, a blade having a perforation, means operatively connected to the handle to rotate the clamping plate on its pivot, a stem slidably mounted in the handle and extending through the perforation in the blade and through said slot and having means to engage the clamping plate to clamp the blade tightly between said plates, the means to rotate the clamping plate comprising an arm slidably mounted in the handle in a direction parallel to the axis of the handle, and means on the stem to actuate said arm, and an operative connection from the arm to the clamping plate.

8. A safety razor having a handle with a longitudinal bore with a slot at one side, a supporting plate connected to the end of the handle, a clamping plate having a keyhole type of slot pivotally connected to one end of the supporting plate, a blade having a perforation, means to engage the blade on the two plates, a stem slidably mounted in said bore and extending through the perforation in the blade and adapted to extend through the keyhole slot when the clamping plate is tilted, a head on said stem to engage the clamping plate, an arm operatively connected to said stem and extending through the slot in the handle and having means to engage the clamping plate, a collar on the stem to engage the arm and actuate said arm to rotate the clamping plate into an open position.

9. A safety razor having a handle with a longitudinal bore and with a slot at one side, a supporting plate connected to the end of the handle, a clamping plate pivotally connected to the supporting plate at one end and having a keyhole type of slot with an enlarged and a relatively contracted portion, a blade having a perforation mounted between the two plates, a stem extending through the bore of the handle, the perforation, and through the keyhole slot and having a head to engage the clamping plate at the reduced section of the keyhole slot, a sleeve slidably mounted in the bore and having an arm extending therefrom through the slot in the handle, a pivoted link connection between the arm and the clamping plate, a collar on the stem to move said sleeve in one direction, and a spring to shift said sleeve in the opposite direction.

10. A safety razor as claimed in claim 9, each plate having transverse ribs with knife-like edges to engage a blade on opposite sides.

11. A safety razor having a handle with a longitudinal bore and a slot from the bore, a supporting plate having a slot at one end, a clamping plate hingedly connected to the supporting plate at the end having the slot, said clamping plate having a keyhole type of slot with a circular and a reduced offset section, means to support a blade between the two plates, a stem extending through the bore and screwthreaded therein, said stem having a head, the head being adapted to pass through the circular section

of the slot when the stem is raised and the 5 clamping plate tilted, a sleeve in the bore, an arm connected thereto and extending through the slot in the handle, and a link connection extending through the slot in the supporting 10 plate and pivotally connected between the arm and the clamping plate, a collar on the stem to engage the sleeve and move said sleeve upwardly when the stem is raised, and a spring to move 15 said sleeve downwardly on disengagement of the collar from the sleeve.

12. A safety razor as claimed in claim 11, a 15 blade mounted between the supporting and clamping plates and having a center perforation with the stem extending therethrough, a pair of end slots, the link extending through one slot and a stud connected to the supporting 20 plate connected through the other slot.

13. A safety razor as claimed in claim 11, a 20 blade mounted between the supporting and clamping plates and having a center perforation with the stem extending therethrough, a pair of end slots, the link extending through one slot and a stud connected to the supporting 25 plate connected through the other slot, a transverse slot connected to each longitudinal slot of the blade, two pairs of studs connected to the supporting plate extending through the transverse slots.

30 14. A safety razor having a handle with a longitudinal bore, a portion of the bore being threaded and there being a slot from the bore, a supporting plate having a slot at one end connected transversely to the end of the handle, 35 said supporting plate having upwardly extending ears at the end having the slot, a clamping plate having downwardly extending ears, a pin- gage through said ears, said clamping plate hav-

ing a keyhole type of slot with a circular and a reduced section, a stem threaded in the bore and extending through the supporting plate and having a head adapted to pass through the circular section of the keyhole slot and engage the 5 upper portion of the clamping plate adjacent the reduced section of the slot, a cupped sleeve 10 slidably mounted on the stem having an arm extending laterally, an ear extending downwardly from the clamping plate, and a link pivotally connected between said ear and the arm, a collar on the stem to engage the lower end 15 of the cupped sleeve, a spring in the bore engaging one end of the bore and the cupped sleeve.

15. A safety razor as claimed in claim 14, a 15 blade having a center perforation through which the stem passes, each end of the blade having a pair of end notches, one pair being adapted to engage the ears of the clamping 20 plate.

16. A safety razor as claimed in claim 14, the 25 handle having a central hub section extending longitudinally and a pair of lateral fins, said fins being in a direction transverse to the sup- porting and clamping plates.

17. In a safety razor, a clamping plate having 30 means to support a blade, a blade having a center perforation, a pair of notches on each end, a center slot extending inwardly from each end and a transverse slot connected to each longitudinal slot, the supporting plate having a pair of studs fitting in each transverse slot, a single stud fitting in one of the longitudinal slots, and a hinged construction at the opposite end en- 35 gaging in each of the end notches.

AXEL S. CARLSON.
